UNITED STATES PATENT OFFICE.

JAMES ELLERY MARBLE, OF ELIZABETH, NEW JERSEY.

CONCRETE-INSERT.

1,145,385.

Specification of Letters Patent.

Patented July 6, 1915.

Application filed February 8, 1915. Serial No. 6,705.

To all whom it may concern:

Be it known that I, JAMES E. MARBLE, a citizen of the United States of America, and a resident of Elizabeth, county of Union, and State of New Jersey, have invented certain new and useful Improvements in Concrete-Inserts, of which the following is a specification.

My invention relates to improvements in what are known as concrete inserts, viz:— devices intended to be set into concrete floors, walls and the like, to facilitate the attachment of various articles, such for example as shaft hangers, pipe supports, etc., to such floors and walls. These inserts are commonly objects of the general nature of a metal socket piece, provided with means whereby they may be firmly interlocked with the concrete, and with means whereby they may be secured to the false work or centering used during the molding of the concrete floor, wall, etc. However, former devices for this purpose have possessed numerous disadvantages which are overcome in the structures for the same purpose herein illustrated and described. In particular, most former devices for the same purpose have not been constructed in such manner that they can be secured with sufficient firmness to the false work or centering, as a result of which former inserts are very frequently displaced, over-turned, and consequently "lost" during the dumping of the concrete mixture around them, and the leveling of the concrete; in fact, it is not unusual in the erection of concrete buildings to lose more than half of the inserts in this manner. Again, as such inserts have been constructed in the past it has been difficult to locate them accurately in their intended positions. The centers of these positions are usually marked on the false work; but the insert being an object of some size, the center mark is covered by the insert when placed, and there is nothing to show that the insert has been properly centered with reference to such center mark.

My invention comprises a novel concrete insert so constructed that it may be secured very firmly to the false work, may be centered accurately and easily with reference to its intended position, and, when the concrete has set about it, is anchored very firmly in that concrete. Furthermore, my insert is so constructed as to permit a considerable latitude of adjustment, with reference to the in-

sert, of the bolt or other member to be supported by that insert.

The objects of my invention are, to improve securing devices such as are commonly termed "concrete inserts," to provide such a device which shall not be liable to displacement, which may be centered readily and easily and which will be held very firmly by the concrete, and to provide a device possessing the above advantages and which is simple and easy to construct, relatively light, and inexpensive, strong, and which affords a wide range of adjustment of the device to be supported with reference to it.

I will now proceed to describe my invention with reference to the accompanying drawings and will then point out the novel features in claims. In said drawings: Figure 1 shows a longitudinal vertical section of one form of my improved concrete insert, set within a body of concrete or the like; Fig. 2 shows a vertical transverse section of the same device so set; Fig. 3 shows a front elevation of the said insert; Fig. 4 shows a side elevation thereof. Fig. 5 is a view similar to Fig. 1, except that the means for holding the insert in place during the placing and setting of the concrete is indicated. Fig. 6 shows a top view of the insert. Fig. 7 shows a sectional perspective of the insert with a T-headed bolt shown in place therein. Fig. 8 shows a transverse vertical section of one form of the bridge piece which I commonly use in connection with the insert, in holding that insert in place during the laying of the concrete, and also, in some instances, for the support of objects by the insert after the concrete has set. Fig. 9 shows a vertical transverse section of an alternative form of the insert. Fig. 10 shows a vertical longitudinal section of such alternative form. Fig. 11 shows a horizontal section of such alternative form, the section being taken on the line $\alpha-\alpha$ of Fig. 10. Fig. 12 is a view similar to Fig. 5, though on a smaller scale, but illustrating the use of a wood screw instead of a bolt for holding the insert to the false work.

Referring first to Figs. 1-8 inclusive: Numeral 1 designates the insert itself, the same being a hollow box-like body having a top 2 and having at its ends extensions 3 provided with enlarged tops 4, whereby the device is anchored in the concrete. For further anchoring of the insert within the concrete, such insert is preferably provided

with a projecting rib or web 5 which, for strength, is preferably located at or about the height of the top 2. In the bottom of the insert there is a slot 6 which preferably extends from one end wall of the insert to the other, ledges 7 being provided, within the insert, and at the two sides of this slot, for the support of a bridge piece such as the bridge piece 8, or for the support of the head of a T-headed bolt 9 (see Fig. 7) or for the support of any other device to be engaged with the insert. In the top 2 of the insert I customarily provide a central hole which is convenient for use in centering the insert, which hole, once the insert has been centered, and secured in place, is commonly closed by a plug 10 of wood or other material, preferably a soft material such as will facilitate the easy removal of such plug when desired, and expand when wet by the concrete to prevent inflow of the liquid concrete mixture into the insert.

In locating this insert I commonly bore a small hole through the centering or false work at the place marked thereon for the center of the insert, and, having placed within the insert a bridge piece, such as the bridge piece 8 of Figs. 1 and 2, or the nearly similar bridge piece 8^a shown in Fig. 8 (such bridge piece being so placed that it is supported at the ends by the ledges 7), I drop a bolt 11 down through the hole in the top 2 of the insert, and through the central hole of the bridge piece 8 or 8^a and through the hole so bored in the centering, and then apply a nut 12 to the bolt and, by screwing up that bolt, I fasten the insert firmly in place with reference to the centering. It is easy to center the insert, with almost absolute accuracy, with reference to the head of this bolt, by the unaided eye; for the head of the bolt will be but little smaller than the hole in the top 2 of the insert, and it is easy for even an unskilled workman to determine whether the hole in the top 2 of the insert is substantially central with reference to the head of this bolt. Of course such centering of the insert with reference to the bolt head is done before the nut 12 is screwed up tight. Once that nut has been screwed up tight, the insert is held so firmly to the centering that such insert will not be displaced by the workmen, during the laying of the concrete. The insert can even be struck violently without being displaced, when so secured in place; for in order to displace that insert, once the nut has been screwed up, it is necessary to crush the wood of the false work.

The insert having been located and secured in place as described, the hole in its top plate 2 is commonly closed by the plug 10, to prevent the concrete from filling the space underneath the top 2, and then the concrete is applied around and above the in-

sert and permitted to set. Not only does the plug 10 prevent larger particles of concrete from entering the insert, but the plug of wood or other suitable material immediately expands when moistened by the concrete and effectively prevents seeping in of the liquid mixture, so that the interior of the insert remains open and unobstructed. When the concrete has set, the nuts 12 and bolts 11 are removed and then the false work is taken down, leaving the insert anchored firmly in the concrete. As will be observed, the bottom of the insert is then flush with the bottom or front wall of the concrete.

In attaching objects, such for example as pipe supports, shaft hangers, and the like, to the inserts, I sometimes use a bridge piece, such as the bridge piece 8 shown in Figs. 1 and 2, which bridge piece may be threaded to receive a correspondingly threaded bolt 13; such bridge piece having preferably, as indicated in Fig. 2, shoulders 14 adapted to engage the sides of the slot 6 and thereby to prevent turning of the bridge piece during the screwing up of the bolt 13; and, desirably, this bolt 13 may be screwed up until it abuts firmly against the plug 10 (held in place by the concrete above it); whereby the unscrewing of the bolt under the influence of vibration is rendered improbable. Or, instead of a bolt such as 13, screwing into a threaded bridge piece 8, I may employ a bolt such as the bolt 9 shown in Fig. 7, having a T-head 15 and having, preferably, flat shoulders 16 beneath its head, such shoulders adapted to engage the sides of the slot 6 and thereby to prevent turning of the bolt. It will be understood that sufficient clearance is provided between the tops of the ledges 7 and the bottom of the top 2 of the insert, to permit the insertion of the head of the bolt with its head 15 parallel with the walls of the slot, and then to permit the bolt to be turned with its head at right angles to the slot and dropped so that its shoulders 16 engage the sides of the slot 6, as indicated in Fig. 7; and it will be understood that the bridge piece 8 may be inserted in similar manner. When a threaded bridge piece 8, to coact subsequently with a bolt such as bolt 13, is used, this bridge piece may also be the bridge piece used for holding the insert in place during the laying of the concrete; but when a T-headed bolt 9 is to be used, then the simpler and cheaper bridge piece 8^a, shown in Fig. 8, is commonly used for the fastening of the insert in place, such bridge piece 8^a being removed after the false work has been removed.

In some cases, instead of boring a hole through the false work and using a bolt such as 11 for holding the insert in place, I use an ordinary wood screw, 17 (Fig. 12) 134

in the same manner. It is easy to center the insert with reference to the center mark on the false work and then to drive such screw, the screw driver being inserted through the 5 center hole in the top 2.

In Fig. 7 the hole in the top 2 of the insert is shown as square; but in many cases this hole is round, as indicated by the shading of the plug 10 in Figs. 1 and 2.

10 It will be understood that this insert permits considerable lateral adjustment of the bolt 13 or 9, with reference to the insert; and the bridge piece 8 may be moved to any desired position from one end of the slot 6 15 to the other end thereof. Most of the inserts heretofore used, and in which provision for such lateral adjustment is made, have been provided with what is known as a "keyhole" slot, *i. e.*, a slot which is much 20 wider at one end than at the other; such wider portion of the slot being provided in order to permit the insertion of the head of a bolt or the like; as a result, relatively 25 small latitude for lateral adjustment of the position of the bolt is permitted in such former devices, and obviously the bolt is not supported when its head is in the larger portion of the slot; but my construction provides full support for the bolt, or bridge 30 piece 8, from one end of the slot to the other. Moreover, the webs of metal forming the ledges 7 have support not only from the sides of the insert, but also from the ends of the insert, and for that reason 35 these webs of metal are much stronger, for equal dimensions and equal quality of material, than is the case when a keyhole slot is provided.

40 Preferably my insert is a malleable iron casting or a steel casting, and therefore its extensions 3 may have such flexibility that, if desired, they can be bent over as indicated in dotted lines in Fig. 1; thus providing additional anchoring in the concrete; 45 and the extensions 3 may be bent over in this manner either before the insert has been placed upon the false work, or afterward.

50 In some cases it is desirable to locate inserts in sloping walls or ceilings, such inserts to support objects located directly beneath the bottoms of the inserts. In such cases, the form of insert shown in Figs. 9, 10 and 11 is convenient. In this form the 55 insert is provided at its bottom with a slot 6, as in the construction shown in Fig. 2, but the ledges 7^a at the sides of this slot are each provided, at about their centers, with a semi-circular recess to receive a T-headed 60 bolt 9^a having its lower side cylindrically

curved. It will be clear that the insert shown in Figs. 9, 10 and 11 can be set at an angle from the vertical, and yet the bolt 9^a will hang vertically.

What I claim is:—

1. An insert for concrete and similar structures comprising a hollow body adapted to be attached to forms for concrete and having integral side and top walls provided with means for engagement with the 70 concrete, said body having an elongated slot in its bottom for the reception of supporting devices and of attaching means for attaching said body to said forms; the top of said body having a centrally arranged opening, 75 whereby the center of the opening can be alined over any desired point of the form.

2. An insert for concrete and similar structures comprising a hollow body adapted to be attached to forms for concrete and 80 having integral side and top walls provided with means for engagement with the concrete, said body having an elongated slot in its bottom for the reception of supporting devices and of attaching means for attaching said body to said forms, the top of 85 said body having a centrally arranged opening, whereby the center of the opening can be alined over any desired point of the form, and a plug of expansible material closing 90 said opening to prevent inflow of liquid concrete into said body.

3. An insert for concrete and similar structures comprising a hollow body adapted to be attached to forms for concrete and 95 having integral side and top walls provided with means for engagement with the concrete, said body having an elongated slot in its bottom for the reception of supporting devices and of attaching means for attaching 100 said body to said forms, and ledges on both sides of said slot extending from one end to the other of the body, the top of said body having a centrally arranged opening closed by a wooden plug, a bridge-piece 105 within the body portion resting on said ledges and slideable therealong and having a threaded opening throughout its length, and a screw threaded member extending through said threaded opening into said 110 body and into engagement with said wooden plug, whereby the loosening of said screw threaded member is prevented.

In testimony whereof I have signed this specification in the presence of two subscribing 115 witnesses.

JAMES ELLERY MARBLE.
